SPOOL AXMINSTER CARPET LOOM

Isaac B. Bassindale, Grasscroft, near
Oldham, EnglandApplication February 21, 1947, Serial No. 730,043
In Great Britain February 16, 1946

4 Claims. (Cl. 139—124)

1

This invention of improvements in or relating to the selvedge mechanism of spool Axminster carpet looms refers more particularly to driving mechanism for imparting reciprocatory movement to the selvedge shuttles in the shuttle races and is primarily intended for use with curved shuttles of large size.

With the use of selvedge shuttles as heretofore constructed, when removing a shuttle for replenishment of yarn, it is necessary to release a tension spring which holds the cam lever in contact with the cam to enable the shuttle driver shaft to be rotated sufficiently to push the shuttles out of the shuttle races in a forward direction for replenishment of yarn. Further, in the operation of a carpet loom employing shuttles as heretofore constructed, when the shuttle is passed through the loop of weft until the weft drops off the blunt end of the shuttle the weft becomes trapped between the shuttle and the rear shuttle driver. It is then necessary to bring the shuttle to rest and reverse the direction of rotation of the shuttle drivers to form a gap between the rear driver and the end of the shuttle through which the weft can slip to be caught by the selvedge cord.

The present invention overcomes this disadvantage by providing the shuttle driver shaft with a clutch coupling whereby the driver shaft may be uncoupled from its driving means by simple movement of a handle without need for interfering with the aforesaid tension springs or disturbance of the cam lever, thus leaving the shuttle driver shaft free to be revolved at will.

The invention further provides means whereby the weft passing along the shuttle may automatically free itself without the necessity for stopping the shuttle and reversing the direction of rotation of the drivers thus effecting a saving of time and facilitating the smooth working of the shuttles.

Shuttle driving mechanism according to the invention includes a driver shaft, rotary shuttle drivers carried by said shaft, a rotary cam, a cam lever operable by said cam, means connected with said cam lever for driving said shaft, and a clutch coupling between said shaft and said shaft driving means, whereby said shaft may be simply uncoupled from said shaft driving means and left free without interference with said cam lever.

A practical embodiment of the invention will now be described with the aid of the accompanying drawings in which only so much of a

2

carpet loom is shown as is necessary for a clear understanding of the invention.

Fig. 1 is a fragmentary side view showing selvedge shuttle driving mechanism according to the invention fitted to a carpet loom; Fig. 2 is a sectional elevation looking in the direction of the arrow A in Fig. 1; Fig. 3 is a fragmentary plan, drawn to a larger scale, of the shuttle race; Fig. 4 is a fragmentary perspective view showing the top weft needle at the finish of a shot with the upper shuttle entering the loop of weft and showing a portion of the carpet being woven; Fig. 5 is a similar perspective view looking at the outer side of the shuttle race and with the shuttles in the same position as in Fig. 4, the removable segment of the shuttle race casing being taken away to expose the interior of the shuttle races.

The same reference characters indicate corresponding parts in the several figures of the drawings.

Referring to the drawings, 10 indicates a vertical driving shaft journaled in bearings 11, 12 on the loom frame 13, the vertical axis of the driving shaft 10 being co-linear with the vertical centre of the circular shuttle races 14. The driving shaft 10 has keyed upon its upper part a bracket 15 formed with two radially projecting arms 16, 17 spaced apart, each of which carries a lever arm adjustable towards and away from the centre of the driving shaft 10 and respectively forming the front drivers for the upper and lower shuttles 20, 21. One of said lever arms, i. e., the upper one, is indicated at 18; the lower arm, not shown, is identical.

For convenience in description reference will only be made to the drive for the upper shuttle 20 but it is to be understood that the drive for the lower shuttle 21 is similar in every respect.

The lever arm 18 is adjustably secured in a groove in the upper face of the arm 16 and is formed on its under side with a small projection 22 adapted to engage in a recess 20a in the upper surface of the shuttle 20 whereby to form a driving connection with said shuttle.

The bracket 15 is furnished with a short spindle 23 spaced in parallelism with the driving shaft 10 in lugs 15a projecting from the bracket 15. Mounted loosely on the spindle 23 in superposed relation are two levers 24, 25 which serve as rear drivers for the respective upper and lower shuttles 20, 21. As before, only the upper driver will be described, the lower driver being identical.

The lever 24 is formed with three arms, the two outermost, and shorter, arms being adapted to engage an adjustable stop 26 on the boss of

the bracket 15 and an adjustable stop 27 on the front arm 16. The central and longer arm of the lever 24 is furnished at its outer end with a freely mounted serrated wheel 28, which normally bears against the blunt end of the shuttle, see Fig. 5.

Freely mounted on the driving shaft 10 below the upper bearing 11 is a toothed pinion 29, the boss 30 of which forms one clutch element of a coupling the other element 31 of which is splined on the driving shaft 10 with freedom for sliding movement thereon in a vertical direction.

The clutch element 31 is embraced by a yoke 32 having a lever handle 33 by means of which the clutch element 31 may be slid on the driving shaft 10 to engage with, or disengage from, the clutch element 30 on the pinion 29. A compression spring 34 encircling the driving shaft 10 between the footstep bearing 12 and the coupling clutch serves normally to hold the clutch in engagement with the pinion 29.

The teeth of the pinion 29 on the driving shaft 10 are enmeshed with the teeth of a horizontal rack 34^a adapted to be traversed horizontally in guides 35 on the loom frame 13 by a cam lever 36 and connecting rod 37. The cam lever 36 is moved in the direction of the front of the loom by a cam 38 and in the opposite direction by a tension spring, or as illustrated in Fig. 1, by two tension springs 39, each connected at one end to the cam lever 36 and at the opposite end to a plate 40 mounted at the free end of a rod 41 secured to the frame 13.

On that side of the shuttle race casing adjacent to the selvedge edge S of the carpet C and between the races 14 and a vertical guide roller 42 moulded in the frame 13 around which roller the selvedge cord SC passes on its way from the shuttle to the selvedge there is slidably mounted a two-armed traverse bar 43 which is traversed backwards and forwards by a lever 44 operated by a cam on the auxiliary tappet shaft of the loom.

The shorter arm 43^a of the traverse bar 43 is formed with an inclined face 43^b adapted, when the traverse bar 43 is moved forward, to cover the gap 45 in the top shuttle race, through which the upper needle N passes, prior to the shuttles moving forward.

The selvedge cord SC is raised to a higher plane by the inclined face 43^b of the traverse bar 43, thereby preventing it from becoming trapped between the shuttle and the race.

The same conditions apply when the shuttles are moved to their rear position, the selvedge cord running up the inclined face of the traverse bar 43 on to the top of the shuttle race, after which the traverse bar 43 is withdrawn to allow the passage of the needle N.

The horizontal and longer arm 43^c of the traverse bar 43 is slidably mounted at the end remote from the vertical arm 43^a in a guide bracket 46 secured to the loom frame, the end of the horizontal arm 43^c adjacent to the vertical arm 43^a being slidably supported on a grooved roller 47 journalled on a pin 48 projecting from the upper shuttle race.

The horizontal arm 43^c is furnished about mid-way of its length with a block 49 having a curved face, and with a pin 50 in spaced relation with the block 49.

The cam-operated lever 44 is oscillatably mounted on a stud 51 carried by the loom frame and its upper part projects between the block 49 and the pin 50 on the horizontal arm 43^c, whereby, when the lever 44 is rocked forwardly, it

presses against the curved block 49 to push the traverse bar 43 forward to cover the gap 45 in the upper shuttle race. When the lever 44 is rocked in the reverse direction, it presses against the pin 50 to return the lever 43 to its initial position.

The shuttle races 14 are circular in plan and the wall of the race member remote from the selvedge edge of the carpet is formed with a removable segment 14^a, Fig. 3, to facilitate placing of the shuttles in the respective upper and lower races. The removable segment 14^a may be provided with apertures, registering with the upper and lower races, or may be hingedly connected to the race member at one side as indicated at 52, Fig. 3, and at its opposite side secured by a catch indicated at 53, Fig. 3, or other easily removable means. The purpose of this formation will be explained later in the description.

The operation of the mechanism is as follows: Assuming the shuttles 20, 21 to be in their extreme rearmost working position, shots of weft are inserted across the loom by the needles N, the ends of which come to rest in the shuttle races, the gap 45 in the upper shuttle race 14 being opened by reason of the traverse bar 43 being moved away. The pinion 29 being clutched to the driving shaft 10, the traversing movement of the rack 34^a brought about by the return movement of the cam lever 36, under the influence of the tension springs 39, rotates the pinion 29 and shaft 10 whereupon the rear drivers push the shuttles a short distance in a forward direction to cause the tapered ends of the shuttles to insert their points through the loops in the weft in the needles N. Fig. 4 shows the upper shuttle about to perform this operation. The needles are then withdrawn leaving the loops of weft around the pointed ends of the shuttles. The shuttles are then moved forward to their extreme forward position.

As the shuttles move forward, the loops of weft slide smoothly over the rounded surfaces of the curved shuttles, the weft passing below each front driver through a slight gap between the projection 22 on the lower side of the driver arm 18 and the recess 20^a in the respective shuttle, the distance between the front and rear drivers being such that, when the rear drivers bear against the adjacent ends of the shuttles, the projections 22 on the front drivers are each moved slightly away from their abutment against the wall of the recess 20^a in the respective shuttle whereby to produce the aforesaid gap.

In the continued forward movement of the shuttles the loop of weft on each shuttle slips over the blunt rear end of the shuttle, the weft catching in a tooth of the serrated wheel 28 and turning the wheel 28 freeing itself from the shuttle to be caught by the selvedge cord SC along which it slides when beaten-up to the fell of the fabric.

As the shuttles are moved forward through the loops of weft, the traverse bar 43 with inclined face 43^b also moves forward to close the needle gap 45 in the top shuttle race, thereby raising the shuttle cord SC to prevent its being trapped. When the shuttles reach the extreme forward position, the traverse bar 43 is withdrawn.

When all the shots of weft are beaten up to form the fabric, the shuttles are returned to their rear position and when approximately mid-way in their traverse the traverse bar 43 is again moved

forward to raise the upper cord SC on to the top of the upper shuttle race.

When the selvedge cords in the shuttles are exhausted the shuttles may be replenished without removing them from the respective races. In 5 order to accomplish this operation, the coupling is declutched from the pinion 29 and the shuttles are pushed around the races by hand until they register with the apertures in the outer wall of the race member, when new cops may be inserted 10 in the respective cop compartments of the shuttles.

Alternatively, if the removable segment of the race member be of the hinged type previously described, said hinged segment may be unfastened 15 and swung back to afford access to the shuttles to enable the shuttles to be removed from the races to facilitate the replenishment of yarn.

Owing to the fact that the weft loops are self-releasing, thus obviating the necessity for stoppage of movement of the shuttles to release the said weft loops the motion is enabled to work smoothly instead of time being wasted to stop and reverse, thus minimising wear and tear.

What is claimed is:

1. Mechanism for driving the selvedge shuttles of a spool Axminster carpet loom incorporating upper and lower shuttle races in which said shuttles are movable, including a driver shaft, rotary shuttle drivers carried by said shaft, a rotary cam, a cam lever operable by said cam, means connected with said cam lever for driving said shaft, and a clutch coupling between said shaft and said shaft driving means whereby said shaft may be simply uncoupled from said driving means and left free without interference with said cam lever.

2. Shuttle driving mechanism as claimed in claim 1, including means for enabling an exhausted shuttle to be replenished without removal from the respective shuttle race.

3. Shuttle driving mechanism as claimed in claim 1, in which the driver shaft is vertical and mounted in an upper bearing, said mechanism including a bracket keyed on said shaft and having a boss, adjustable stops on said boss, said

bracket being formed with two radially projecting arms spaced apart, a lever arm being carried by each projecting arm, each of said lever arms being adjustable towards or away from the axis of said shaft, said lever arms respectively forming the front drivers for the upper and lower shuttles, adjustable stops on said front drivers, a short spindle journaled in said bracket in parallelism with said shaft, two levers mounted loosely in superposed relation on said spindle and serving as rear drivers for the upper and lower shuttles, each of said last mentioned levers being formed with three arms, the two outermost arms of said last mentioned levers being adapted to engage the stops on said boss and the stops on the front driver arms, a serrated wheel normally bearing against the blunt end of the respective shuttle and carried by the central arm of each respective three-armed lever, a toothed pinion freely mounted on the driver shaft below said upper bearing, and forming one clutch element of a coupling, a co-operative coupling element splined to said shaft with freedom for sliding movement along said shaft, and means for engaging and disengaging said coupling elements.

4. Shuttle driving mechanism as claimed in claim 1 in which the loom frame is furnished with guides, and the driver shaft is provided with a toothed pinion, said mechanism including a horizontal rack enmeshed with said pinion and adapted to be traversed horizontally in said guides by the cam lever alternately towards and away from the front of the loom, and at least one tension spring connected to said cam lever and to 35 the loom frame for moving the cam lever in the direction away from the front of the loom.

I. B. BASSINDALE.
